[57] CLAIM

The ornamental design for a bottle opener, as shown and described.

DESCRIPTION

FIG. 1 is a perspective view of a bottle opener showing my new design;

FIG. 2 is a right side elevational view thereof, the left side elevational view being a mirror image;

FIG. 3 is a rear elevational view thereof;

FIG. 4 is a bottom plan view thereof;

FIG. 5 is a top plan view thereof;

FIG. 6 is a front elevational view thereof;

FIG. 7 is an additional perspective view of a bottle opener showing my new design; and,

FIG. 8 is a sectional view thereof along the line 8—8 in FIG. 4.
